CLAIM

The design for a medical support pillow, as depicted herein in FIGS. 1-7.

DESCRIPTION

FIG. 1 is a perspective view of the invention.

FIG. 2 is a front view of the invention.

FIG. 3 is a view of the back of the invention.

FIG. 4 is view of one side of the invention.

FIG. 5 is the opposing side view of the invention.

FIG. 6 is a top view of the invention; and,

FIG. 7 is a view of the bottom of the invention.
